(57) **CLAIM**

What is claimed is the ornamental design for a cable gripper, as shown and described.

DESCRIPTION

FIG. 1 is a perspective view of a cable gripper, showing the new design;

FIG. 2 is a front elevational view thereof, the rear elevational view being a mirror image thereof;

FIG. 3 is a left-side elevational view thereof, the right-side elevational view being a mirror image thereof;

FIG. 4 is a top plan view thereof, the bottom plan view being a mirror image thereof; and,

FIG. 5 is a cross-sectional view thereof, taken generally along lines 5—5 of FIG. 4.

The broken lines in the figures depict portions of the cable gripper that form no part of the claimed design.
